SECTIONAL SANDWICH PLATE

Henry Kowsky, Rochester, N. Y.

Application May 26, 1949, Serial No. 2,898

Term of patent 3½ years

(Cl. D44—15)

To all whom it may concern:

Be it known that I, Henry Kowsky, a citizen of the United States, residing at Rochester, in the county of Monroe and State of New York, have invented a new, original, and ornamental Design for Sectional Sandwich Plate, of which the following is a specification, reference being had to the accompanying drawing, forming part thereof.

In the drawing:

Fig. 1 is a top plan view of a sectional sandwich plate, showing my new design;

Fig. 2 is a vertical sectional view taken on line 2—2 of Fig. 1; and

Fig. 3 is a side elevational view thereof.

I claim:

The ornamental design for a sectional sandwich plate, substantially as shown.

HENRY KOWSKY.
